YARN CARRIER CONTROL MECHANISM

Christian F. Meyer, Wyomissing, Pa., assignor to
Textile Machine Works, Wyomissing, Pa., a
corporation of Pennsylvania

Application December 17, 1936, Serial No. 116,389

12 Claims. (Cl. 66—127)

My invention relates to means for laying yarns in recurrent sequence to the loop-forming mechanisms of straight, or full-fashioned stocking, knitting machines to produce "ringless" and other fabrics.

It is well known that, when a stocking fabric is knitted by a single carrier from a single yarn, weak lengths, or sections of reduced diameter occurring in the thread are sometimes formed into successive courses immediately adjacent to sections of standard diameter at opposite sides thereof. This feature produces what are known as "rings" or "shadows", in the form of horizontal streaks across the blank, to avoid which, it has been suggested to knit the blank from separate identical yarns by interspersing the yarns to avoid having weak lengths of any one yarn appear in successive courses.

Although variations of the number of yarns, and the order and character of the courses, have been suggested, a standard practice is to lay three separate yarns in recurrent sequence. This number has operated to best advantage from various viewpoints, such as producing a fabric substantially commercially free from rings, and adapting itself to practical methods and machines for producing the fabric.

Also, as far as I am aware, each of the high-production machines for this purpose heretofore employed, has produced its results by the use of a special friction-box mechanism, or single-box structure to which the three carriers are attached, and from which they are released, in sequence.

Thus, although three carriers are operated in sequence, each to lay a length of yarn only in every third stroke of the special friction box, the latter is subject to the same wear and frictional heat as a single box laying the same thread in every course. Such box starts each stroke substantially instantaneously after being heated by the next previous stroke, to transmit such heat to the friction rod and to itself be further heated without appreciable interval for cooling between strokes.

These special friction boxes carry relatively complicated mechanisms for sequentially attaching the boxes to, and releasing them from, the several carriers. This feature requires exact construction and timing for register between slides or levers on the boxes and dogs on the carrier bars, and also requires special holding devices for the bars whereby the boxes may release one carrier at the end of each stroke and pick up another carrier.

According to one form of my invention, each of the plurality of carriers for laying the sequential yarns, during the production of stockings of the same style, is constantly connected to a friction box individual thereto, and instead of having the carriers alternately connected to, and disconnected from, one and the same friction box, the carrier selection is effected by alternately clamping the boxes to, and releasing them from, the friction rod. Thus, with three friction boxes spaced from each other along the rod, and operating alternately, the heat of friction generated between the rod and each box is separate from the heat of friction generated by the other boxes, whereby to greatly enhance the ability of the machine to operate at maximum efficiency for long periods of time at high speed. The device may be operated to actuate the three friction boxes as disclosed, or be rearranged so as not to operate the three boxes, but to actuate only one box for any desired purpose.

In modern high-speed operation of full-fashioned stocking and other straight knitting machines, the impacts between the full-speed carrier bars and the end stops are of such magnitude and frequency as to jar the machine, to shake parts out of place, and to cause asynchronous operation, stoppages of the machines, defective fabrics, expense, delay, excessive noise and other undesirable results.

To overcome these objections, provisions have been made in the form of a shock-reducer rod parallel to the friction rod which is reciprocated at a speed less than the speed of the friction rod. Hinges or levers have been provided on the friction boxes, to act as side projections which can be moved to inactive positions away from the shock reducer rod. Each of these levers, in active position, is adapted to engage collars or projections on the shock reducer rod, near the ends of the carrier bar strokes, at a time when the shock reducer rod is traveling at its reduced speed in the same direction as the higher speed friction rod.

The retarding action effected when the friction-box hinge engages the collar on the shock reducer rod, as the carrier bar approaches one of its stops, causes the box to slide relative to the friction rod, while still being driven by it, such that the carrier bar engages its stop with negligible impact.

Means have heretofore been provided to move these hinges between active and inactive positions, but not, so far as I am aware, in such sequence as to enable a plurality of friction boxes

to cooperate with such shock reducer means in producing "ringless" or other fabrics requiring operation of the yarn carrier bars in repetitive series cycles.

5 One object of my invention is to provide novel means for operating a plurality of yarn carrier elements, or bars, of a knitting machine in repetitive series cycles, thereby to effect the production of ringless and other fabrics, or portions 10 thereof, requiring the operation of the yarn carrier elements in this manner.

Another object of the invention is to provide means for selectively actuating a plurality of devices, such as friction boxes, to alternately effect 15 connections and releases between actuating means, such as a friction rod, and yarn carrier elements, such as carrier bars, in repetitive sequence or successive similar series cycles during a single fabric completing cycle, as in producing 20 a stocking blank.

Another object is to provide a yarn carrier selector of the friction rod and box type that is more efficient from the standpoint of heat generation in that it receives less heat from, and 25 releases less heat to, the friction rod or actuator, and is thereby more effective in high-speed operation.

Another object is to provide a device of the above-indicated character that is more certain in 30 its operation, that is less likely to get out of order, and that more positively holds a friction box or equivalent connector unit in inactive position.

Another object is to maintain yarn carriers 35 in constant connection to friction box or equivalent means in permanent alignment with a friction rod or other actuator to avoid shifting connections between selectively operated carriers and the actuator.

40 A further object of the invention is to avoid the requirement of extremely precise dimensions and accurate fit between the parts of a yarn carrier selector, and to provide a device of this character that is capable of novel cooperation with 45 shock reducing means.

Additional objects of my invention are to avoid 50 the disadvantages above mentioned, and to provide a novel mechanism free therefrom, that is more rugged and durable, and that is economical to manufacture and effective in its operation.

With these and other objects in view, which 55 will become apparent from the following detailed description of the mechanism illustrated in the accompanying drawings, the invention represented by this mechanism resides in its novel elements, features of construction and arrangements of parts in cooperative relation, as herein-after more particularly set forth and claimed.

In the drawings:

60 Figure 1 is a top plan view on a reduced scale of a multi-section full-fashioned knitting machine embodying the invention, the view being shortened by distance breaks, and parts being omitted;

65 Fig. 2 is a perspective view of certain parts involved in laying three yarns alternately in succeeding courses of a fabric during the knitting thereof;

70 Fig. 3 is a diagram indicating the yarn courses and the sequence of laying these courses by the machine of the invention;

75 Fig. 4 is a view taken substantially along the line 4-4 of Fig. 7, enlarged relative thereto, and having a distance break;

Fig. 5 is a view taken along the line 5-5 of Fig. 4, on a reduced scale relative thereto;

Fig. 6 is a view on a reduced scale, taken along the line 6-6 of Fig. 4;

Fig. 7 is a view taken along the line 7-7 of Fig. 1, enlarged relative thereto;

Fig. 8 is a view similar to Fig. 7, taken along the line 8-8 of Fig. 4;

Fig. 9 is a sectional view taken along the line 9-9 of Fig. 4;

Fig. 10 is a view similar to Fig. 7, but on a reduced scale relative thereto, and showing further parts;

Fig. 11 is a view taken along the line 11-11 of Fig. 7, enlarged relative thereto;

Fig. 12 is a detail sectional view taken along the line 12-12 of Fig. 7;

Fig. 13 is a detail view of parts along the line 13-13 of Fig. 4;

Fig. 14 is a view taken along the line 14-14 of Fig. 12;

Fig. 15 is a perspective view of friction boxes, a friction rod, carrier bars and associated parts including yarn guide fingers on the bars as related to a portion of a stocking fabric, indicated on a very greatly increased scale relative to the other parts of the figure;

Fig. 16a is a view similar to a portion of Fig. 8 of a friction box, with the parts positioned as at one stage of operation;

Fig. 16b is a view similar to Fig. 16a of a second friction box, with its parts as positioned during the time that the parts of the box of Fig. 16a are positioned as therein shown;

Fig. 16c is a view similar to Fig. 16b of a third friction box, with its parts as positioned during the time that the parts of the boxes of Fig. 16a and Fig. 16b are positioned as shown in these figures;

Fig. 17a, Fig. 17b and Fig. 17c are views similar to Fig. 16a, Fig. 16b and Fig. 16c, respectively, of the three separate friction boxes thereof, with the parts as simultaneously positioned at a subsequent stage of operation; and

Fig. 18a, Fig. 18b and Fig. 18c are views similar to Fig. 17a, Fig. 17b and Fig. 17c, respectively, of the three separate friction boxes thereof, with the parts as simultaneously positioned at a further stage of operation.

In practicing the invention, in the example given, a longitudinally stationary elongated element or rod is placed parallel to a usual friction rod or actuator and to a shock-reducer rod, and three friction boxes or carrier-moving devices provided, each of double-friction box character for alternately clamping the box to the stationary and friction rods.

The invention includes the provision of means connected between the clamps of any one friction box or equivalent device for correlating the release of the box from one rod to the gripping by the box of the other rod and vice versa, so that, when released from the friction rod, the box is immediately held by the stationary rod, and when released from the latter is immediately moved by the friction rod.

The selection of the carriers is thus effected by means, such as the friction rod and a friction box, which are in constant alignment, or ready for instant cooperation, with each other without shifting any element from one member to another as with the above-mentioned special friction boxes.

A rotatable shaft extending parallel to the above-mentioned rods, operates as a single means responsive to operation of the machine to oper-

ate rotatable cams through gear wheels of a mechanism carried by each box and splined to the shaft for rotation therewith and movement therealong. The cams actuate the double-friction box clamps as aforesaid to alternately grip and release the friction and stationary rods independently of movement which may be given to either of these rods. By arranging the above-mentioned rotatable cams in proper angular relation about the axes of rotation thereof, and having active and inactive perimetral portions proportioned accordingly, the device may be adapted to produce ringless fabric. The structure is adaptable to laying yarns of different 15 thicknesses, colors, texture and other characteristics, in cyclic relation to produce stripes or other pattern effects. Also, by rearrangement of parts, the number of boxes operating in sequence may be varied.

20 In the case of the three-carrier operation, the centers of the active surfaces of corresponding cams of the respective boxes are disposed one hundred and twenty degrees apart, with the centers of the inactive surfaces correspondingly 25 spaced, so that with each of three friction boxes connected to its associated carrier bar, the sequential carrier bar action is effected by alternately connecting the boxes to, and disconnecting them from, the friction rod, with the boxes being 30 held to the stationary rod when released from the friction rod, or from a similar reversely movable carrier-actuator element. A member, hinged or pivoted to each box, coacts with collars on a rod operating at a reduced speed, such as 35 half the speed of the friction rod or actuator whereby, near the end of each stroke, the hinged member engages a collar on the reduced-speed rod. This action retards the travel of the box and causes the associated carrier bar to engage 40 the corresponding end stop with negligible impact.

According to the invention, these hinged members of the respective boxes are operated in sequence between active and inactive positions 45 relative to the collars, depending upon whether a box is active or inactive, to place the inactive hinged elements out of the way of the collars.

The drawings illustrate parts of a Reading full-fashioned knitting machine necessary for an 50 understanding of the invention. Other parts and the operation thereof are well known in the art, as set forth in the "Reading" Full Fashioned Knitting Machine Catalogues, copyrighted 1920, 1929 and 1935, and published by the Textile 55 Machine Works, Reading, Pennsylvania, and a booklet entitled "Knitting Machine Lectures" published in 1935 by the Wyomissing Polytechnic Institute, Wyomissing, Pennsylvania.

Referring to Figs. 1, 7 and 10, the framework of 60 the machine therein shown comprises end frames 15, center frames 16, a front beam 17, a back beam 18, a center bed 21 and a front bed 22.

A cam shaft 25, and a loop-forming mechanism including a needle-bar assembly N and a 65 sinker-head assembly S, are mounted on this framework.

Yarn carrier bars 1 to 8, inclusive, are supported by brackets, one bracket 21 of which is shown in each of Figs. 7 and 10 secured to the 70 center bed 21. The bars 1 to 8, inclusive, have fingers attached thereto for delivery of yarn to the needle-bar and sinker-head assemblies N and S. Three of these fingers F¹, F² and F³ are attached to the bars 1, 2 and 3, respectively, as 75 shown in Fig. 2 for laying yarns Y₁, Y₂ and Y₃,

respectively, to the loop-forming mechanism. The yarns are fed to the fingers from yarn packages, bobbins or cones 29 on bobbin pins 31 in a moistening box or humidifying unit H at the rear of the machine, from which each yarn passes 5 through an eyelet 33 in the top wall of the unit H, against a stationary guide rod 34, through a "snapper" 37 on a shaft 38, and against another stationary guide rod 41 to one of the fingers.

The carrier bars 1 to 8, inclusive, are selectively 10 reciprocated longitudinally, to lay the yarns to the loop-forming mechanism, by a usual and well known coulier-motion mechanism (not shown) operating through a friction rod 42 and friction boxes, such as the boxes B¹, B² and B³, 15 to be more fully set forth. Full-course reciprocating movement of the carrier bars is controlled by usual end stops E.

The coulier-motion mechanism also actuates 20 slur cock boxes 45 for effecting certain operation of the sinker head assembly S in synchronism with the needle bar assembly N. The latter is operated from the cam shaft 25, through a needle bar lifting shaft 46, a needle bar lifting lever 47 and a forked member 48 (Fig. 2) constituting 25 part of a needle-presser linkage.

Reciprocating motion of the narrowing or fash- 30 ioning points (not shown) is controlled by nuts 51 on spindles 52, which are actuated from the cam shaft 25 by narrowing head cam actuating 35 levers 54. The spindles 52, and other spindles (not shown) for actuating the end stops E, are controlled in forward, reverse and reset movements by mechanism R.

A shock reducer rod 55, extending parallel to 35 the friction rod 42, is actuated by the coulier-motion mechanism at a speed less than the speed of the friction rod, such as half the speed of the latter. The rod 55 carries collars, one collar 56 of which is shown in Figs. 5, 6 and 13. These 40 collars are clamped to the rod for engagement by members 57 hinged by pins 58 to housing members 61 of the friction boxes B¹, B² and B³.

A rod 65, similar to the friction rod 42, except 45 that the rod 65 is stationarily mounted on the machine frame, is disposed in closely adjacent parallel relation to the friction rod.

Each housing 61 is of two-part or double-housing character embracing both rods 42 and 65. Each box carries a slide 62 having a handle 63 and 50 a lug 64 whereby the boxes B¹, B² and B³ are detachably connected to the bars 1, 2 and 3, respectively, by placing the corresponding lugs in slots 70 of dogs 71, 72 and 73 on the bars 1, 2 and 3.

Members 66 and 67 in the housing 61, surrounding 55 the rods 65 and 42, respectively, each have a bottom portion enclosing friction shoes 68, and a top portion or bridge 78, in which are journaled shafts 74 and 75.

The shafts 74 and 75 of the box B², carry disc 60 cams 76a and 77a, respectively, for action against usual leaf springs 69 disposed on the shoes 68. Similarly the shafts 74 and 75 of the box B¹ carry disc cams 76b and 77b, respectively, and the shafts 74 and 75 of the box B³ carry disc cams 76c and 77c, respectively.

A bracket 82, bridged across both members 66 and 67, and secured in grooves 83 by screws 84, supports members 85 and 86 journaled therein, 70 Fig. 4.

The member 85, as better seen in Fig. 12, is of 75 shaft-like character having a slotted end 88 fitting a head 89 on the shaft 74. The head 89 is of rounded character having opposite flat sides fitting the end 88, Fig. 14. The member 85 further

has a pinion 91, a bearing portion 92 journaled in the bracket 82, and an eccentric stud 93 disposed in a slot 96, Fig. 13, in the associated hinged member 57, whereby rotation of the member 85 alternately moves the member 57 between active and inactive positions relative to the collars 56 on the half-speed shock-reducer rod 55.

The member 86 is constructed similarly to the member 85, with the exception of the eccentric stud 93, which is omitted, and a bearing portion 97 which corresponds to, but is smaller in diameter than, the bearing portion 92. A slotted end 98, similar to the end 88, is provided on the member 86 for similar cooperation with a head 99 on the shaft 75. Likewise, a pinion 101 on the member 86 is similar to the pinion 91 on the member 85.

The bracket 82 has a forked portion 102 (Figs. 4 and 6) embracing a member 105 between collars 106 thereon whereby movement of the box by the friction rod carries the member 105 slidably along a control shaft 107. The latter is axially stationary, but rotatable, whereby, through the medium of a spline 108, the member 105 is rotated by the shaft 107 at the ends of coulisse-motion strokes, as will appear. A gear wheel 109 on the member 105 engages the pinions 91 and 101 on the members 85 and 86, respectively.

Upon rotation of the shaft 107, the disc cams 76a and 77a of the box B2 are operated to clamp the box B2 to the stationary rod 65, when releasing it from the friction rod 42, and to release the box from the stationary rod 65, when clamping it to the friction rod 42. Thus, the shoes of the box clamping it to the friction rod are never shifted to clamp another rod, nor are the shoes clamping the box to the stationary rod shifted to clamp any other rod, but each set of shoes remains in position adjacent to, and co-operates only with, its own rod, as distinguished, for instance, from a carrier selector in which a single member carried by a friction box shifts from one carrier to another. The disc cams 76b, 76c, 77b and 77c are similarly operated relative to the boxes B1 and B3. The centers of the active surfaces of the discs 76a and 77a of the box B2 are disposed in one hundred and eighty degree relation to each other for this purpose, as also are the centers of the active surfaces of the discs 76b and 77b of the box B1, and of the discs 76c and 77c of the box B3. The center of the inactive surface of each cam is disposed one hundred and eighty degrees from its active surface. On each cam 77a, 77b and 77c, the active surface occupies substantially one hundred and twenty degrees of the cam perimeter. The active surface of each cam 76a, 76b and 76c occupies substantially two hundred and forty degrees of its perimeter.

With the discs 76a and 77a individual to the box B2, the discs 76b and 77b individual to the box B1, and the discs 76c and 77c individual to the box B3 related to each other in this manner, and directly interconnected by the shaft 107, a pattern repeating device is provided whereby the boxes will grip and release the friction rod in one, two, three order. During each operation of the pattern repeating device, the friction rod is gripped, and the stationary rod is released by one box, and the friction rod is released and the stationary rod is gripped by another rod.

Referring to Figs. 16a, 16b and 16c, the parts are disposed in positions assumed at the time that the parts of Figs. 2 and 15, respectively, are in the positions therein shown.

At this time, as indicated in Figs. 2 and 3, the carrier finger F2 of the carrier bar 2 is about to be moved from right to left, to effect which movement, as seen in Fig. 16a, the cam 77a has its active portion in active position clamping the box B2 to the friction rod 42 and the cam 76a is in position releasing the box from the stationary rod. Simultaneously with this condition, as seen in Fig. 16b, the cams 76b and 77b of the box B1 are in active and inactive position relative to the rods 65 and 42, respectively, and, as seen in Fig. 16c, the cams 76c and 77c of the box B3 are in active and inactive position relative to the rods 65 and 42, respectively. Thus, during the time that the box B2 is being moved to the left, the boxes B1 and B3 are idle, since they are clamped to the stationary rod 65 and released from the friction rod 42.

By reason of the angular extent of the active cam portions about the individual axes thereof and the angular relation of the cams of the respective boxes to each other, the parts as indicated in Figs. 16a, 16b and 16c, although conditioned for the above mentioned right to left movement of the box B2 while the boxes B1 and B3 are idle, are also positioned such that upon the next simultaneous clockwise movement of all the cams to the position shown in Figs. 17a, 17b and 17c, the box B2 will be released from the friction rod 42 and clamped to the stationary rod 30 65, the box B1 will remain gripped to the stationary rod and released from the friction rod, and the box B3 will be clamped to the friction rod and released from the stationary rod for moving the carrier bar 3 and the finger F3 from 35 left to right.

At the end of the latter left to right movement, when the next simultaneous clockwise movement of all the cams places them in the positions shown in Figs. 18a, 18b and 18c, the 40 box B3 will be released from the friction rod and clamped to the stationary rod, the box B2 will remain clamped to the stationary rod and released from the friction rod, and the box B1 will be released from the stationary rod and clamped 45 to the friction rod for movement from right to left.

The next operation in the above mentioned cycle, is the same as that shown by Figs. 16a, 16b and 16c with the others following in the 50 order described; these operations being repeated throughout the single fabric completing cycle producing the "ringless" area.

A lever 112, pivotally mounted at a fixed position on the back narrowing shaft 114, has one 55 arm 115 carrying a cam follower roller 117 for cooperation with cams 121 and 122 (Fig. 11). The latter are secured by an angle member 123 and screws 124 to the slur cock boxes 45. These boxes are mounted on a connecting bar 126 which 60 reciprocates on a stationary slur cock slide bar 127. A spring 128 biases the lever 112 clockwise, as viewed in Figs. 7, 8 and 10, toward the cams 121, 122.

Another arm 131 of the lever 112 is pivotally connected by a pin 132 to one end of a longitudinally adjustable link 133. The other end of the link 133 is pivotally connected by a pin 130 to an arm 136 projecting radially from the control shaft 107 on which the arm is loosely mounted. The arm 136 has a portion 137 to which a pawl 138 is pivoted by a pin 139. A tension spring 142 is connected between a pin 143 on the portion 136 and a pin 144 in a projection 70 75

145 on the pawl 138, to bias the pawl toward a ratchet wheel 147 keyed to the control shaft 107. The arm 131 of the lever 112 is provided with a projection 134 which carries a screw 135 for cooperation with the shaft 65 to limit clockwise movement of the lever 112, Fig. 9.

Upon reciprocation of the slur cock boxes 45, the cams 121 and 122 alternately engage the follower 111, at opposite ends of a coulier-motion stroke, to actuate the lever 112, and to notch the ratchet wheel 147 and the control shaft 107 in a counterclockwise forward movement. By this action, the gear wheel 109 advances the pinions 91 and 101 for giving the rotary disc cams 15 76a and 77a the motion above described for simultaneously gripping the corresponding friction box to the friction rod 42 and releasing it from the stationary rod 65. The cams alternately reverse this action to simultaneously grip the box 20 to the stationary rod and release it from the friction rod. These actions of the boxes are performed to operate the yarn carrier bars 1, 2 and 3, respectively, in one, two, three order, as above explained.

25 When this is done, the yarns Y1, Y2 and Y3 are laid as indicated in Fig. 3 whereby a single cycle of the yarn-laying action resides in first laying one yarn, such as the yarn Y1, from left to right, as indicated, leaving the carrier finger 30 F1 of the yarn Y1 at the right end of its stroke, picking up the carrier finger F2 at the right end, moving it to the left to lay the yarn Y2 in the second course, releasing the finger F2 at the left-end of its stroke, and picking up the 35 finger F3 at the left side of the loop-forming mechanism to lay the yarn Y3 in the third course.

These operations are effected by connecting and disconnecting entire friction boxes relative to the 40 friction rod 42, as above set forth, in contradistinction to the former practice of constantly operating one special friction box, and sequentially operating a slide or like member on the special box relative to the three carrier bars 45 which it is to operate.

In the above described one, two, three cycle of operation of the boxes B1, B2 and B3, by rotation of the member 85 (Fig. 12) of each box, the main carriers are given the advantage of 50 cooperation with the reduced speed shock reducing mechanism without having this mechanism interfere in any way with the effective operation of the carriers.

Of course, the improvements specifically shown 55 and described by which the above described results are obtained, may be modified in many ways without departing from the invention herein disclosed and claimed.

I claim:

60 1. In a knitting machine, a friction rod, friction boxes on said rod each connected to a separate yarn carrier bar, and a pattern repeating device for operating a plurality of the boxes in predetermined order and successively repeating 65 a certain cycle of friction box operation including directly interconnected means individual to the friction boxes and each arranged to connect one of the friction boxes to the friction rod so that during each operation of said pattern repeating device one of the friction boxes is connected to the friction rod and another is disconnected therefrom.

70 2. In a knitting machine, friction rod means, a plurality of friction boxes, a rotatable shaft extending parallel to the friction rod means, and

means including rotatable cams carried by the boxes and actuated by the shaft for clamping the boxes to, and releasing the same from, the friction rod means in predetermined relation determined by the positions of the cams about the 5 axes thereof relative to each other.

3. In a knitting machine, friction rod means, a plurality of friction boxes, cams journaled in said boxes for clamping and releasing the boxes relative to the friction rod means, a rotatable 10 shaft extending parallel to the friction rod means, means for turning the shaft, and means movable along the shaft axis gearing the shaft to the cams, the cams of the respective boxes being related about the axes of rotation thereof in 15 accordance with a given relation of operation of the boxes.

4. In a knitting machine, friction rod means, a plurality of friction boxes, cams journaled in said boxes for clamping and releasing the boxes 20 relative to the friction rod means, a rotatable shaft extending parallel to the friction rod means, pawl and ratchet means for turning the shaft step by step, and means slidable on the shaft 25 gearing the shaft to the cams, the cams of the respective boxes being related about the axes of rotation thereof in accordance with a given relation of operation of the boxes.

5. In a knitting machine, friction rod means, a plurality of friction boxes, holding means 30 along the friction rod, cam means journaled in each box for releasing the box from the friction rod means and causing said holding means to hold the box when the box is so released, said cam means operating to operatively connect the 35 box to the friction rod means and to release the box from said holding means for such connection, a rotatable shaft extending parallel to the friction rod means, means for turning the shaft, and means movable along the shaft axis gearing 40 the shaft to the cams, the cams of the respective boxes being related about the axes of rotation thereof in accordance with a given relation of operation of the boxes.

6. In a straight knitting machine, the combination with a friction rod, and carrier bars, of a stationary rod parallel to the friction rod and to the carrier bars, a friction box including a two-part housing the parts of which embrace the friction rod and the stationary rod, respectively, clamping shoes and springs in said friction-box parts, means including cams rotatively journaled on the friction box for alternately clamping the shoes to the friction rod and to the stationary rod, respectively, reciprocable 55 cams, and means including a lever pivoted to a stationary part of the machine carrying a follower for actuation by said reciprocable cams and mechanism responsive to operation of the follower by the latter cams for actuating the 60 rotative cams.

7. In a straight knitting machine, the combination with a friction rod, and yarn-carrier bars, of a stationary rod parallel to the friction rod and to the carrier bars, a plurality of friction 65 boxes each including a two-part housing the parts of which embrace the friction rod and the stationary rod, respectively, clamping shoes and springs in said friction-box parts, means including cams rotatively journaled on each friction 70 box for alternately clamping the corresponding shoes to the friction rod and to the stationary rod, respectively, means correlating the rotative cams of the several friction boxes to operate the latter in sequence whereby carrier bars 75

associated with the respective boxes are operated in cycles, reciprocable cams, and means including a lever pivoted to a stationary part of the machine carrying a follower for actuation by the reciprocable cams and mechanism responsive to operation of the follower by the latter cams for actuating the rotative cams.

8. In a knitting machine, the combination with a yarn carrier, a reversely movable actuator for 10 the yarn carrier, and means reversely movable at a speed less than the speed of the actuator, of a device for moving the carrier including means for operatively connecting the device to, and releasing it from, the actuator, and means 15 for effecting operative relation between said device and said reduced speed means and disassociating the device and the reduced speed means from each other.

9. In a knitting machine, the combination with 20 a yarn carrier, a reversely movable actuator for the yarn carrier, and means reversely movable at a speed less than the speed of the actuator, of a device for moving the carrier including means for operatively connecting the device to, 25 and releasing it from, the actuator, said connecting and releasing means including means for effecting operative relation between said device and said reduced speed means when the device is connected to the actuator and disassociating 30 said device and the reduced speed means from each other when the device is released from the actuator.

10. In a knitting machine, the combination with 35 a yarn carrier, a reversely movable actuator for the yarn carrier, and means reversely movable at a speed less than the speed of the actuator, of holding means, a device for moving the carrier including means for alternately operatively connecting the device to, and releasing 40 it from, the actuator simultaneously with releasing it from, and operatively connecting it to, said holding means, said connecting and releasing means including means for effecting oper-

ative relation between said device and said reduced speed means when the device is connected to the actuator and disassociating said device and the reduced speed means from each other when the device is held by the holding means. 5

11. In a straight knitting machine, the combination with carrier bars, stops for the bars, a friction rod, and a rod reciprocable at a speed less than the speed of the friction rod, of a stationary rod, a friction box connected to one of 10 said carrier bars, including means for alternately clamping the box to, and releasing it from, the friction rod simultaneously with releasing it from, and clamping it to, said stationary rod, said means including means for effecting operative 15 relation between the box and said reduced-speed rod for reducing shocks of said one carrier against its stops when the box is clamped to the friction rod and preventing operative relation between the box and the reduced-speed rod when the box 20 is clamped to the stationary rod.

12. In a straight knitting machine, the combination with carrier bars, stops for the bars, a friction rod, and a rod reciprocable at a speed 25 less than the speed of the friction rod, of a stationary rod, a plurality of friction boxes each connected to one of the carrier bars and each including means for alternately clamping the box to, and releasing it from, the friction rod simultaneously with releasing it from and clamping 30 it to, said stationary rod, and means for operating said clamping and releasing means of the several boxes in a predetermined cycle and effecting operative relation between the boxes and the reduced speed rod for reducing shocks of impact of the cyclically operated bars with the corresponding stops when the boxes are clamped to the friction rod and preventing operative relation between the boxes and the reduced-speed 35 rod when the boxes are clamped to the stationary rod. 40
